(Cl. D33—6)

FIG. 1.

FIG. 2.

FIG. 3.

FIG. 4.

FIGURE 1 is a front elevational view of the dressing table of my new design wherein one pedestal is narrower than the other so as to present an asymmetrical appearance:

FIGURE 2 is a perspective view thereof, the sides not shown being plain and substantially the same as the sides shown;

FIGURE 3 is a front elevational view of the dressing table wherein the two pedestals are of uniform width so as to present a symmetrical appearance; and

FIGURE 4 is a perspective view thereof, the sides not shown being plain and substantially the same as the sides shown.

This application is a division of my prior copending application Serial Number D. 65,460, filed June 5, 1961, for a dresser.

I claim:

The ornamental design for a dressing table, as shown and described.
